FISHHOOK SHARPENER

Lloyd L. Gaines, Lawrence, Kans.

Application September 19, 1949, Serial No. 116,462

13 Claims. (Cl. 51—57)

1

This invention relates to new and useful improvements in fishhook sharpeners, and relates particularly to sharpeners of the grinder type.

The principal object of the present invention is the provision of a device suitable for grinding the points of fishhooks which have been dulled or turned, thereby placing the hooks in condition for further use. It is particularly common for the fine points of fishhooks to be turned or bent by contact with a metal or other hard surface.

Another object is the provision of a fishhook sharpener including a planar abrasive block and means for reciprocating said block, and means for positioning the tip of a fishhook in operative relationship to said block.

Another object is the provision, in a sharpener of the class described wherein a reciprocal abrasive block is urged against a fishhook for grinding the same, of means for mounting said block which is yieldably tiltable relative to said fishhook and yieldably urged against said fishhook, whereby said block will contact said fishhook properly at all times as it is reciprocated.

A further object is the provision in a sharpener of the class described wherein a fishhook is sharpened by an abrasive block urged laterally against the point thereof and reciprocally movable longitudinally relative to said point, of means for urging said block against said fishhook as it moves toward the point of the hook, and means for retracting said block out of contact with said hook on its return stroke.

Other objects are simplicity and economy of construction, ease and convenience of operation, efficiency, and adaptability for sharpening various fine pointed articles.

With these objects in view, as well as other objects which will appear in the course of the specification, reference will be had to the drawing, wherein:

Figure 1 is a side elevation of a fishhook sharpener embodying the present invention, with a fishhook shown in operative relationship thereto.

Figure 2 is an enlarged, fragmentary, vertical longitudinal section of the sharpener, with parts left in elevation.

Figure 3 is a horizontal section taken on line III—III of Fig. 2, with parts left in elevation.

Fig. 4 is a fragmentary section taken on line IV—IV of Fig. 3, with the abrasive block and associated parts shown in the depressed position.

Fig. 5 is a section taken on line V—V of Fig. 2.

Fig. 6 is a section taken on line VI—VI of Fig. 2.

Fig. 7 is a side elevation of a modified form of the sharpener, with a fishhook shown in operative relationship thereto.

2

Fig. 8 is an enlarged side elevation of the sharpener shown in Fig. 7, with parts broken away.

Fig. 9 is an irregular section taken on line IX—IX of Fig. 8.

Like reference numerals apply to similar parts throughout the several views, and in the preferred form shown in Figs. 1 to 6, the numeral 2 applies to a body member comprising an elongated rectangular box made of plastic, wood, metal or other suitable material, and having a top wall 4, side-walls 6, and end-walls 8. The box is closed at the bottom by a cover 10 secured to the box by any suitable means such as screws 12.

15 At the forward end of the body member, or the left end as viewed in Figs. 1 to 4, a transverse portion of top-wall 4 is offset downwardly to form a ledge 14, the inner vertical surface 16 of which faces the interior of the body member. Surface 16 and the end surface 18 of top-wall 4 are slightly spaced apart longitudinally of the body member.

20 Surface 16 has a vertical groove 28 formed therein substantially in the midline of the body member. Said groove is relatively deep at its upper end, and tapers gradually toward its lower end. The point of a fishhook 22 is inserted downwardly into said groove as best shown in Figs. 2 and 4, the taper of said groove corresponding approximately to the taper of the barb portion of the hook. The portion of the hook adjacent the barb lies against surface 18 of the top-wall, and assists in holding the hook steadily in position.

25 An upwardly projecting boss 24 is formed on top-wall 4, the flat forward face 26 of said boss being coplanar with surface 18. This boss provides an extension of surface 18 against which the fishhook may be braced, and also forms a guard tending to prevent pricking of the fingers with the hook. It will be noted, as shown in Fig. 4, that

30 with the fishhook positioned as described, the hook projects inwardly from surface 16. 35 An arm 28 extends longitudinally within the upper portion of body member 2. At its rearward end, said arm is formed to present a cross-head 30 which is axially bored to engage pivotally a pin 32 which extends horizontally between side-walls 6 and is fixed in said side-walls. A torsion spring 34 is carried about cross-head 30 and has its central portion engaging arm 28

40 and its end portions engaging the inner surface of top-wall 4, whereby said arm is urged pivotally upwardly. At its forward end arm 28 is provided with a head 36. An operating rod 38 is 45 pivotally attached at its lower end to said head by means of a horizontal pivot pin 40, and ex-

50

tends upwardly through a loosely fitting hole 42 provided in top-wall 4. Operating rod 38 is provided at its upper end with a button 44, which the operator may engage with his thumb for reciprocating arm 28 pivotally about pin 32.

At its forward end, arm 28 is provided with a forward axial extension 46 of reduced diameter on which a tubular carrier 48 is mounted for axial sliding movement. A pin 50, fixed in said carrier and extending diametrically therethrough, passes through a slot 52 formed in arm extension 46. This prevents rotation of the carrier and limits the axial movement thereof. At its forward end carrier 48 is provided with two forwardly projecting, horizontally spaced apart ears 54. A forwardly opening cup 56 carrying a block 58 of abrasive material, is mounted pivotally between said ears, said cup being provided with horizontally projecting coaxial trunnions 60 journaled in said ears.

Trunnions 60 extend outwardly past said ears to points adjacent side-walls 6 of the body member. An inwardly projecting cam 62 is formed integrally with each of side-walls 6 immediately beneath the normal or raised positions of trunnions 60. Each of said cams is provided with a rearwardly and downwardly inclined surface 64, which engages the associated trunnion when arm 28 is pivoted downwardly, thereby camming cup 56 and carrier 48 rearwardly on arm extension 46. Said cup and carrier are normally urged forwardly by a helical spring 66 disposed around carrier 48 and bearing respectively at its opposite ends against cup 56 and head 36 of arm 28. A movable cam arm 68 is pivotally mounted in each side-wall 6 immediately behind and below the normal raised position of trunnions 60, by means of pivot pins 70 extending outwardly through said side-walls. Said lever arms extend downwardly from said pivot pins, and have their wedge-shaped lower ends normally resting against cam surfaces 64, as shown in Fig. 2. Each lever arm 68 is resiliently urged against cam surface 64 by a spring 72 fixed at one end to side-wall 6 by a screw 74, and bearing at its opposite end against the rearward side of the cam lever.

The operation of the device is substantially as follows. Normally arm 28 is urged upwardly by spring 34 and abrasive block 58 is urged forwardly by spring 66. The abrasive block is prevented from contacting surface 16 of the body member by the engagement of carrier pin 50 in the forward end of slot 52, but the abrasive block will be too close to surface 16 to permit the proper insertion of the fishhook 22 in groove 20. The operator first grasps body member 2 in his hand and with his thumb depresses button 44 to pivot arm 28 downwardly. When the upper edge of abrasive block passes below the lower end of groove 20, the point of the fishhook may be inserted downwardly into groove 20 as previously described. As button 44 is still further depressed, trunnions 60 contact surfaces 64 of arms 62 and are thereby urged rearwardly, thereby retracting the abrasive block by forcing carrier 48 along arm extension 46 against the pressure of spring 66. At the same time, the trunnions engage and pivot cam arms 68 rearwardly against the pressure of springs 72. As arm 28 reaches the lowermost point of its travel, the trunnions pass below the lower ends of cam arms 68, and springs 72 urge said arms forwardly to contact cam surfaces 64. The operator then releases button 44, and arm 28 is returned to its upper position by spring 34. During the return stroke, trunnions

60 ride along the rearward surfaces of cam levers 68, and are thereby cammed still further rearwardly. As arm 28 reaches the upper limit of its travel, trunnions 60 pass above the upper ends of cam arms 68, and the abrasive block 58 and its carrier are moved forwardly by spring 66 until said abrasive block contacts the point of the fishhook.

Button 44 is then repeatedly depressed and released, the abrasive block wiping against the point of the fishhook during its downward stroke, and being retracted out of contact with said fishhook during its upward or return stroke. This prevents the possibility that the abrasive block might strike and bend or dull the point of the hook during its return stroke. Furthermore, the tiltability of the abrasive block on trunnions 60, and the bodily movement of the abrasive block longitudinal to arm 28 provided by the slidability of carrier 48 on said arm, permits the block to be urged squarely against the hook driving its entire stroke over said hook. This provision compensates for the fact that otherwise the abrasive block would not move in a plane, but angularly about pivot pin 32, and permits the face of the abrasive block to move substantially in a plane. The yieldable mounting of the abrasive block also permits it to follow the contours of the fishhook point to a considerable extent. The point of the fishhook may be turned axially in groove 20 to a limited degree, thereby presenting different sides of said point to the abrasive block. A screw 76 is threaded vertically through boss 24 of the body member, said screw extending inside of the body member and being positioned to contact the abrasive block cup 56 at the upper end of its stroke. This screw may be adjustably set to regulate the length of the stroke of the abrasive block over the point of the fishhook.

Figs. 7, 8, and 9 show a modification of the invention wherein the body member 79 is substantially similar to body member 2 of the preferred form except that the top-wall 4 is not provided with a hole for an operating rod. Arm 78, corresponding to arm 28 of the preferred form, does not have a connection for an operating rod, but has a shoulder 80 formed thereon against which spring 66 bears. An arm 82 integral with cross-head 88 of arm 78, extends rearwardly and downwardly from said cross-head, and has a slot 84 formed longitudinally therein. A handle member 86 is formed at one end to present a cross-head 88 which is mounted pivotally on a pin 90 which extends between and is fixed in side-walls 6. Said pin is parallel to pivot pin 32, and is disposed adjacent the lower rearward corner of the body member. Handle 86 extends downwardly from cross-head 88 through a window 92 formed in the bottom cover 94 of the body member, and is turned to extend forwardly in spaced apart relation from said cover. A pair of spaced apart parallel arms 96 extend upwardly and forwardly from cross-head 88. A pin 98 extending between said arms parallel to pin 90 carries for rotation a roller 100, which is disposed within slot 84 of arm 82.

Thus body member 79 and handle 86 form in combination a scissors-type hand grip, the repeated operation of which will cause arm 78 to pivot oscillatably in the same manner as arm 28 of the preferred form. The structure and operation of the modified device are otherwise the same as that of the preferred form.

It is apparent that a fishhook sharpener having several advantages has been produced. It

is simple, economical, and efficient. It is convenient and easy to operate and not likely to get out of order. The pivotal and yieldable mounting of the grinding block permits it to accommodate itself to fishhooks having various types of points. The retractability of the grinding block provides that the grinding will be performed only toward the point of the hook.

Although I have shown specific embodiments of my invention, it is apparent that many minor variations of construction and operation could be made without departing from the spirit of the invention.

What I claim as new and desire to protect by Letters Patent is:

1. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinally to said arm, resilient means urging said abrasive block outwardly to contact the tip portion of said fishhook laterally, and means for pivotally reciprocating said arm.

2. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinal to said arm and for pivotal movement about an axis parallel to the pivotal axis of said arm, a spring carried by said arm and resiliently urging said abrasive block outwardly to contact the tip portion of said fishhook laterally, and means for pivotally reciprocating said arm.

3. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinal to said arm, resilient means urging said abrasive block outwardly to contact the tip portion of said fishhook laterally, means for pivotally reciprocating said arm whereby said abrasive block moves in a direction substantially parallel to the axis of the point of said fishhook, and means for retracting said abrasive block away from said fishhook as it moves toward the point of said fishhook.

4. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, a carrier member carried for longitudinal sliding movement on the free end portion of said arm and having forwardly projecting longitudinal ears, a forwardly opening cup disposed between said ears and having trunnions carried pivotally by said ears, said trunnions being parallel to the pivotal axis of said arm, an abrasive block fixed in said cup, a spring carried by said

arm and urging said cup forwardly, whereby said abrasive block is urged laterally against the point of said fishhook, and means for pivotally reciprocating said arm.

5. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, a carrier member carried for longitudinal sliding movement on the free end portion of said arm and having forwardly projecting longitudinal ears, a forwardly opening cup disposed between said ears and having trunnions carried pivotally by said ears, said trunnions being parallel to the pivotal axis of said arm, an abrasive block fixed in said cup, a spring carried by said arm and urging said cup forwardly, whereby said abrasive block is urged laterally against the point of said fishhook, means for pivotally reciprocating said arm, and cam members carried by said body member and adapted to engage said trunnions to retract said abrasive block away from said fishhook as said block moves toward the point of said fishhook.

6. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, a carrier member carried for longitudinal sliding movement on the free end portion of said arm and having forwardly projecting longitudinal ears, a forwardly opening cup disposed between said ears and having trunnions carried pivotally by said ears, said trunnions being parallel to the pivotal axis of said arm, an abrasive block fixed in said cup, a spring carried by said arm and urging said cup forwardly, whereby said abrasive block is urged laterally against the point of said fishhook, means for pivotally reciprocating said arm, fixed cams carried by said body member and adapted to contact said trunnions as said abrasive block moves away from the point of said fishhook to cam said block and said carrier rearwardly along said arm, movable cam arms each pivoted at one end to said body member and having its opposite end resting against the surface of one of said fixed cams, and resilient means urging said cam arms against said fixed cams, whereby as said abrasive block is moved away from the point of said hook said trunnions will pivot said cam arms away from said fixed cams and pass beyond the free ends of said cam arms, and whereby as said abrasive block is moved toward the point of said hook said trunnions will be retained by said cam arms in a position retracted away from said hook.

7. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinal to said arm and for pivotal movement about an axis parallel to the pivotal axis of said arm, a spring carried by said arm and resiliently urging said abrasive block outwardly to contact the tip portion of said

fishhook laterally, an operating rod pivoted at one end to said arm adjacent the free end thereof and projecting outwardly through a hole provided therefor in said body member, whereby said arm may be manually reciprocated.

8. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinal to said arm and for pivotal movement about an axis parallel to the pivotal axis of said arm, a spring carried by said arm and resiliently urging said abrasive block outwardly to contact the tip portion of said fishhook laterally, an operating rod pivoted at one end to said arm adjacent the free end thereof and projecting outwardly through a hole provided therefor in said body member, whereby said arm may be manually pivoted in one direction, a spring carried by said body member and urging said arm pivotally in the opposite direction, and adjustable means for limiting the pivotal movement of said arm.

9. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinal to said arm and for pivotal movement about an axis parallel to the pivotal axis of said arm, a spring carried by said arm and resiliently urging said abrasive block outwardly to contact the tip portion of said fishhook laterally, a crank integral with said arm, a handle member pivotally mounted in said body member and having a lever arm fixed to said handle and operatively engaging said crank, said handle projecting outwardly from said body member and forming in conjunction therewith a scissors-type hand grip, whereby said arm may be pivotally reciprocated.

10. A fishhook sharpener comprising a hollow body member having an aperture therein for receiving the tip portion of a fishhook, said body member being formed to prevent lateral movement of said fishhook, an arm pivoted at one end in said body member about an axis transverse to the axis of the point of said fishhook, an abrasive block carried at the opposite end of said arm for movement longitudinal to said arm and for pivotal movement about an axis parallel to the pivotal axis of said arm, a spring carried by said arm and resiliently urging said abrasive block outwardly to contact the tip portion of said fishhook laterally, a crank integral with said arm and having a longitudinal slot formed therein radially to the pivotal axis of said arm, a handle member pivoted in said body member on an axis parallel to the pivotal axis of said arm, a crank integral with said handle, and a roller carried rotatably by said last named crank and disposed in

said slot of the first named crank, said handle projecting outwardly from said body member and forming a scissors-type hand grip in conjunction therewith.

11. A fishhook sharpener comprising a body member, an abrasive block having a substantially planar face, means supporting said block in said body member for oscillating movement in a direction substantially parallel to the face thereof, and for movement transversely to said face, said body member being formed to position a fishhook with the point portion thereof adjacent said block face and substantially parallel to the direction of oscillation thereof, means whereby said block may be oscillated, and resilient means urging said block transversely of its face whereby said face is urged against said fishhook point.

12. A fishhook sharpener comprising a body member, an abrasive block having a substantially planar face, means supporting said block in said body member for oscillating movement in a direction substantially parallel to the face thereof, for movement transversely to said face, and for pivotal movement about an axis parallel to the face of said block and transverse to the direction of oscillation thereof, means whereby said block may be oscillated, and resilient means urging said block transversely of its face whereby said face is urged against said fishhook point.

13. A fishhook sharpener comprising a body member, an abrasive block having a substantially planar face, means supporting said block in said body member for oscillating movement in a direction substantially parallel to the face thereof, and for movement transversely to said face, said body member being formed to position a fishhook with the point portion thereof adjacent said block face and substantially parallel to the direction of oscillation thereof, resilient means urging said block transversely of its face whereby said block may be oscillated and guide means carried by said body member and operably engaging said abrasive block, whereby said block is retracted out of engagement with said fishhook point as it oscillates in one direction.

LLOYD L. GAINES.
